(57) **CLAIM**

The ornamental design for a surgical bur kit holder assembly as shown and described.

DESCRIPTION

FIG. 1 is perspective view of a surgical bur kit holder assembly according to the present invention;

FIG. 2 is another perspective view of a surgical bur kit holder assembly according to the present invention;

FIG. 3 is a front elevation view of the surgical bur kit holder assembly;

FIG. 4 is a right side elevation view of the surgical bur kit holder assembly;

FIG. 5 is a left side elevation view of the surgical bur kit holder assembly;

FIG. 6 is a rear elevation view of the surgical bur kit holder assembly;

FIG. 7 is a top plan view of the surgical bur kit holder assembly; and,

FIG. 8 is a bottom plan view of the surgical bur kit holder assembly.

The broken lines in the drawings depict environmental subject matter and form no part of the patented design.

1 Claim, 8 Drawing Sheets
